US00D994416S

(12) **United States Design Patent** (10) Patent No.: **US D994,416 S**
(45) Date of Patent: ** Aug. 8, 2023

(54) **BABY BOTTLE**

(71) Applicant: **Ember Technologies, Inc.**, Westlake Village, CA (US)

(72) Inventors: **Clayton Alexander**, Westlake Village, CA (US); **Daren John Leith**, Agoura Hills, CA (US); **Christopher Thomas Wakeham**, Solana Beach, CA (US); **Mikko Juhani Timperi**, San Marcos, CA (US); **Martin Gschwandtl**, San Francisco, CA (US)

(73) Assignee: **Ember Technologies, Inc.**, Westlake Village, CA (US)

(**) Term: **15 Years**

(21) Appl. No.: **29/867,251**

(22) Filed: **Oct. 17, 2022**

Related U.S. Application Data

(63) Continuation of application No. 29/727,478, filed on Mar. 11, 2020, now Pat. No. Des. 967,666, which is a continuation of application No. 29/660,106, filed on Aug. 17, 2018, now Pat. No. Des. 878,849.
